[57] CLAIM

The ornamental design for hand dryer, as shown.

DESCRIPTION

FIG. 1 is a front elevational view of the hand dryer showing our new design;

FIG. 2 is a top plan view of the hand dryer.

FIG. 3 is a bottom plan view of the hand dryer.

FIG. 4 is a left side elevational view of the hand dryer. The hand dryer of FIGS. 1-4 is intended for mounting on a wall with the rear surface (not shown) against the wall. The rear of the hand dryer is plain and devoid of any ornamental features.

Fig. 2.
